UNITED STATES PATENT OFFICE.

EUGENE L. SNYDER, OF CANTON, OHIO.

DESIGN FOR A DRAWING INSTRUMENT.

55,538.

Specification for Design.

Patented June 22, 1920.

Application filed October 22, 1919. Serial No. 332,572. Term of patent 3½ years.

To all whom it may concern:

Be it known that I, EUGENE L. SNYDER, a citizen of the United States, residing at Canton, in the county of Stark and State of Ohio, have invented a new, original, and ornamental Design for a Drawing Instrument, of which the following is a specification, reference being had to the accompanying drawing, forming part thereof.

In the drawings: the figure is an elevation of my drawing instrument.

I claim:

The ornamental design for a drawing instrument, substantially as shown.

EUGENE L. SNYDER.
